[57] CLAIM

The ornamental design for a snow skiing boot drying device, as shown and described.

DESCRIPTION

FIG. 1 is a perspective view of a snow skiing boot drying device, showing my new design;
FIG. 2 is a bottom plan view thereof;
FIG. 3 is a right side elevational view thereof;
FIG. 4 is a top plan view thereof;
FIG. 5 is a left side elevational view thereof;
FIG. 6 is a right end elevational view thereof;
FIG. 7 is a left end elevational view thereof.

The ski boots shown in broken lines in FIG. 1 are shown for illustrative purposes only and do not form a part of the claimed design. In FIGS. 1, 3 and 5 the drying hoses are understood to repeat uniformly and continuously across the entire indicated area.
